DESIGN FOR A LAMP OR SIMILAR ARTICLE

William F. Masterson, Decatur, Ill., assignor to Faries Manufacturing Company, Decatur, Ill.,
a corporation of Illinois

Application June 19, 1946, Serial No. 130,861

Term of patent 3½ years

(Cl. D48—20)

To all whom it may concern:

Be it known that I, William F. Masterson, a citizen of the United States and a resident of the city of Decatur, in the county of Macon and State of Illinois, have invented a new, original, and ornamental Design for a Lamp or Similar Article, of which the following is a specification, reference being had to the accompanying drawing, forming a part thereof.

On the drawing:

I claim:

The ornamental design for a lamp or similar article, as shown.

WILLIAM F. MASTERSON.
